HOWARD W. MATHESON AND JULIAN C. SMITH, OF MONTREAL, QUEBEC, CANADA.

ELECTRODE.

Application filed August 23, 1924. Serial No. 733,721.

This invention relates broadly to improvements in electrodes, and more particularly to electrodes for use in electric steam generating or water heating units of the water resistance type.

The primary object of this invention is to provide a construction of such a type that the formation of non-condensable gases, principally hydrogen and oxygen, is greatly reduced or eliminated.

A further object of the invention is to secure as nearly as possible a uniform current density over the whole surface of the electrode and in the water itself between the electrodes.

A still further object of the invention is to provide construction of such a type as to ensure a vigorous circulation of the water.

The electrodes at present in use in water resistance electric steam generators, such as shown in Swiss Patent No. 30,925 to Revel, are usually cylindrical members disposed axially vertically at such distance from a complementary electrode that a discharge may take place through intervening water, and it was previously supposed that the current density was approximately uniform over the entire surface and that the electric discharge took place without arcing. It has been, however, discovered that although the two electrode surfaces may be parallel, the current density of the surface is by no means uniform, being greatest at the bottom. This non-uniformity of current density is now believed to be due to electro-dynamic forces and to the large volume of steam arising over the surface of the inner electrode, the insulating effect of the steam increasing with the height of the electrode. Therefore, the current density becomes much greater at the bottom where the steam film is thinnest and increases to such a point that arcing takes place under ordinary conditions. Thermal decomposition of the steam results and cooling of the gases takes place so rapidly that recombination of the hydrogen and oxygen is not effected. Rapid deterioration of the lower parts of the electrodes is experienced; and furthermore, the circulation of the water in the boiler is rather poor.

The factors contributing towards the formation of hydrogen and oxygen in the steam may therefore be classified as follows:—

(1) Non-uniform current density of the

electrode surface, with consequent increase 55 in the current density at the bottom of the electrode until arcing takes place, causing thermal decomposition of the water vapour.

(2) Overheating of the electrode itself, due to the poor circulation of the water and 60 the non-uniform current density.

It has been discovered that in the operation of an electric boiler of the type described, the voltage drop is largely at the surface of the high tension electrode and 65 therefore the largest evolution of steam is at the surface of the electrode; with the result that if the steam is allowed to remain in contact with the discharge surface of the electrode, it forms an insulating jacket 70 around the electrode increasing in thickness from the bottom to the top of the electrode and thereby increasing the current density at the lower end of the electrode where the steam film is thinnest. This increase or concentration of current density is believed to 75 be largely responsible for the arcing which has been found to occur. The quality of the water is also a considerable factor in the arcing tendency at any definite voltage. If 80 the water is impure giving low resistance, the voltage should be lowered in order to maintain the current density below the point at which arcing begins. It may be mentioned that the arcing referred to is not power arcing 85 or arcing between electrodes, but merely arcing from the surface of the inner electrode to the water itself. While the arcing is chiefly objectionable on account of the thermal decomposition of water which it 90 causes, it is objectionable for other reasons, such as destructive effect on the electrode.

According to the present invention the electrode may be constructed in various ways in order to minimize or almost entirely 95 eliminate arcing and the formation of non-condensable gases by ensuring a great uniformity of current density from top to bottom of the electrode and by removal of steam from the discharge surface of the electrode. The accompanying drawings show several of the many forms which the electrode may take in order to produce these results. Briefly it may be stated that the electrode instead of being a single continuous surface is preferably made up of a number of separate members or segments with the object of presenting a number of separate

discharge surfaces with channels between for the escape of steam. These surfaces are so disposed that the separation of steam therefrom is facilitated and the steam permitted to rise without passing over the discharge surfaces above. The arrangement also has the disadvantage of ensuring better circulation of water in the boiler with consequent effective cooling of the electrode.

10 In the accompanying drawings illustrating certain, but by no means all possible, embodiments of the invention:—

Fig. 1 is a vertical sectional view of a boiler with the improved electrode therein.

15 Fig. 2 is a cross sectional view on the line 2—2, Figure 1.

Figs. 3, 4 and 5 are views showing on an enlarged scale as compared with Figure 1, various forms of electrode segments.

20 Referring more particularly to the drawings, 11 designates a boiler provided with an inner shell or lining 12, spaced from the boiler but electrically and mechanically connected thereto. The lower end of the boiler 25 may be provided with a downwardly extending leg or settling chamber 13, from which a bleeding pipe 14 leads for discharge of surplus or impure water to regulate the level or electric conductivity of the water in the 30 boiler. Water may be admitted to the boiler by any suitable means as through a pipe 15 having communication with the interior of the boiler at points around the surface thereof.

35 For purposes of illustration only one electrode is shown disposed concentrically in a boiler, and may be regarded as connected in a single phase circuit or to one phase of a two-phase, three-phase, or poly-phase circuit, and the boiler may be regarded as connected to another phase or as grounded. It will be understood that the invention applies to any arrangement of electrodes, i. e., one or more to a boiler and that the discharge may be between the electrode and the 40 boiler or between an electrode and a complementary ground member within the boiler or between concentrically arranged similar electrodes.

50 The form of electrode illustrated comprises a central stem 16 and a series of spaced frusto-conical plates 17, or equivalents, supported in suitable manner from the central stem which may also serve as an 55 electrical conductor for all the plates. It will be understood, however, that the plates may be insulated from the stem and supplied with current by a separate conductor. Preferably the plates increase in outside and 60 inside diameter from the lowermost upwards but there may be no increase in either diameter or the increase may be in only one diameter. Also, the plates are preferably substantially parallel, and if desired the 65 lowermost may be substantially conical

as shown. The outer edges of the plates are preferably rounded but may be thickened or of bulbous cross-section as shown at 18. This arrangement of plates has the advantage not only of giving a substantially 70 uniform distribution of current with cooling of the electrode, but at the same time removes the steam from the active surface of the electrode.

75 Other forms of electrodes are shown in Figures 3, 4 and 5 and embody the use of spaced bars or tubes arranged in substantially frusto-conical form and provided with means for supporting the same from the central stem 16. The structure shown in Figure 3 embodies a single bar or tube 19 bent in spiral-helical form and connected, as by welding, to spacers 20 which hold the various turns of the helix in properly spaced relation and which are in turn mounted on the arms of a spider or other suitable contrivance for supporting the structure from a central stem.

80 Figure 4 discloses a structure differing from that of Figure 3 only in that the bar or tube 19 is replaced by a series of rings 21 secured to the supports 20.

85 Figure 5 shows an arrangement differing from the preceding figures in that the bars 22 composing the discharge surface are arranged to point toward the focal point of the frusto-conical structure instead of extending circumferentially as in the previous forms.

90 In all these modifications excellent cooling is obtained but the construction is not as advantageous as the solid plate construction on account of the tendency for steam to rise between the bars and therefore through the discharge zones. To avoid this condition as much as possible the bars should be closely spaced.

95 The evolution of steam is greatest at the surface of the electrode, as previously explained, and therefore in the present segmental type of electrode the discharge is between the outer surfaces of the electrode segments and the inner shell. Steam formed at these outer surfaces rises into contact with the inner surface of the segment next above and flows thence upwardly through the central orifice of the annular segment and through the corresponding orifices of all segments above. In no case should the steam generated at a lower segment flow in any 100 considerable amount over the active surface of any segment above. The gradual increase in diameter of the segments from the lowest to the highest while not essential is advantageous and serves two purposes: Firstly, it ensures that little or no steam rising from below will flow through the discharge zone of segments above; and secondly, it provides a central passage through the electrode, the 105 cross sectional area of which passage in-

creases from bottom to top to accommodate the increasing volume of steam toward the top. The establishment of a definite current of steam rising through the centre of 5 the electrode induces a vigorous circulation of water in the boiler, which circulation of water serves to uniformly cool the electrode and also to maintain the conductivity of the water substantially uniform throughout 10 the boiler.

Many modifications may be made in the form of the electrode segments or divisions, and it will therefore be understood that the invention is not limited to the details of construction and arrangement herein illustrated, but embraces all modifications and arrangements which produce the results above described.

By the use of electrodes of the general 20 design above described, it is found in actual practice that the amount of non-condensable gases, principally hydrogen and oxygen, is greatly reduced. The amount of hydrogen developed in an electric boiler of previously 25 known design has been found to run between 10 to 50 parts per 1,000,000 parts of steam produced, or even more; whereas with an electrode of the type described and with water of the same characteristics, the free 30 hydrogen drops to $\frac{1}{2}$ to 5 parts per 1,000,000 parts of steam and is usually less than one part. This reduction is obtained with a definite type of water and definite current density, and it is to be understood, of course, that the amount of hydrogen will vary depending on the characteristics of the water and the current density. The following example of results will serve to illustrate.

40 Using an installation comprising three boilers each connected to one phase of a three-phase system and a good commercial water, it is found that with a voltage of 6,600 and total amperage of 2,200, giving 45 about 24,000 kilowatts total input at an average current density of .5 amperes per square inch, that the average of hydrogen gas produced in a series of ten tests was .85 parts per 1,000,000 parts of steam produced, which is approximately the same 50 amount of hydrogen as that found in steam from ordinary coal-fired boilers.

Having thus described our invention, what we claim is:—

55 1. An electrode for water resistance steam generators and the like, comprising a series of annular superposed spaced discharge members and a central conducting and supporting stem connected to said members at intervals around the circumference thereof, whereby a steam passage is formed within the annulae, continuous from top to bottom of the electrode.

60 2. An electrode for water resistance steam generators and the like, comprising a series

of superposed annular frusto-conical discharge members increasing in diameter progressively from the lowermost, and a conducting and supporting stem therefor disposed within the annulae.

70 3. An electrode for water resistance steam generators and the like, comprising a series of superposed annular frusto-conical discharge members increasing in diameter progressively from the lowermost and supporting means therefor disposed within the annulae.

75 4. An electrode for water resistance steam generators and the like, comprising a series of superposed annular discharge plates rounded at their outer edges, and a conducting and supporting stem therefor disposed within the annulae.

80 5. An electrode for water resistance steam generators and the like, comprising a series of superposed annular discharge plates thickened and rounded at their outer edges, and a conducting and supporting stem therefor disposed within the annulae.

85 6. An electrode for water resistance steam generators and the like, comprising a series of frusto-conical annular plates thickened and rounded at their outer edges and nested in spaced relation, and means for supporting the plates.

90 7. An electrode for water resistance steam generators and the like, comprising a series of frusto-conical annular plates nested in spaced relation and progressively increasing in outside diameter from the lowermost plate upwards, and means for supporting the plates and conducting electric current to or from the same.

95 8. An electrode for water resistance steam generators and the like, comprising a series of superposed electrode members adapted to be disposed at different distances from a complementary electrode, the active surface areas of such members being proportioned to the distance from the companion electrode, the direction of current flow and the conductivity of water at different levels, to the end that a substantially uniform current density is obtained at all parts of the active surface of the electrode.

100 9. An electrode for water resistance steam generators for use within a complementary member comprising a hollow inverted frusto-conical electrode body constituting an upwardly enlarging steam conduit within a tubular discharge zone, and means for directing steam from the discharge zone into the conduit.

105 10. An electrode for water resistance steam generators, comprising a hollow body defining a vertically disposed upwardly enlarging steam flow passage, said body having passages inclining upwardly from its active surface and leading into the vertical passage for transfer of steam from the ac-

tive surface of the electrode into the vertical passage.

11. An electrode comprising a series of upwardly tapering hollow members arranged in superposed relation and increasing progressively in diameter from the lowermost, said members combining to define a

passage increasing in size from the bottom upwardly, and means connecting the members together.

In witness whereof, we have hereunto set our hands.
